DESIGN FOR A DRESS

Helen Berry, New York, N. Y.

Application April 20, 1938, Serial No. 76,617

Term of patent 3½ years

To all whom it may concern:

Be it known that I, Helen Berry, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

My design is characterized by the specific button arrangement on the waist, skirt and sleeve portions of the specific dress as shown.

I claim:

The ornamental design for a dress substantially as shown and described.

HELEN BERRY.
